UNITED STATES PATENT OFFICE

149,405

DESIGN FOR A FLIGHT ENGINEER'S TRAINER OR SIMILAR DEVICE

John G. Dodds, North Hollywood, Angus D. MacKillop, Glendale, and Clarence C. Sansom, Studio City, Calif., assignors to Lockheed Aircraft Corporation, Burbank, Calif.

Application June 10, 1946, Serial No. 130,580

Term of patent 7 years

(Cl. D71—1)

To all whom it may concern:

Be it known that we, John G. Dodds, Angus D. MacKillop and Clarence C. Sansom, citizens of the United States, residing at North Hollywood, Glendale and Studio City, county of Los Angeles, State of California, respectively, have invented a new, original, and ornamental Design for a Flight Engineer's Trainer or Similar Device, of which the following is a specification, reference being had to the accompanying drawings, forming a part thereof.

Figure 1 is a perspective view of a flight engineer's trainer showing the design and illustrating the front and one end of the flight engineer's trainer, the characteristic features of the design appearing in full lines;

Figure 2 is a view illustrating the rear of the flight engineer's trainer; and

Figure 3 is a side view illustrating the other side of the flight engineer's trainer.

The dotted line showing of a chair in Figures 1 and 3 is for illustrative purposes only.

We claim:

The ornamental design for a flight engineer's trainer or similar device, substantially as shown and described.

JOHN G. DODDS.
ANGUS D. MACKILLOP.
CLARENCE C. SANSOM.
